UNITED STATES PATENT OFFICE.

ERNEST EDGAR CRANE, OF MINNEAPOLIS, MINNESOTA, ASSIGNOR TO AMERICAN MANGANESE STEEL COMPANY, OF CHICAGO, ILLINOIS, A CORPORATION OF MAINE.

LATCH GUIDE FOR DREDGE BUCKETS.

Application filed October 2, 1925. Serial No. 59,997.

This invention relates to a guide for the latch which holds in closed position the swinging door of a dredge bucket or other structure requiring to be latched in situations where latching mechanism is liable to encounter destructive influences; and the invention has for its object to provide a latching mechanism in which the latch plate or keeper that receives the bolt will be protected from the impact of objects past which it is moving during operation of the bucket.

The invention proceeds upon the principle of providing a deflecting guard or shoe upon the hinging member or door in a position which will bring the guard into protecting relation to the keeper when the hinging member is latched, for instance, by embodying the guard in the structure of that one of the latch bar guides which is near the keeper. The preferred embodiment of the invention involves the use of a pair of wings or buffers on opposite sides of the keeper, constructed with deflecting surfaces guarding approach to the keeper from the sides and preferably also from the rear, said surfaces being provided, for the sake of lightness of construction, by flanges upstanding from the attaching base of the latch bar guide, but being forwardly offset in the plane of the hinging member, in order that the guard may project on opposite sides of the keeper; and these guarding surfaces preferably increase in altitude, measured from the base of the guide, as they approach the keeper. The preferred embodiment of the invention further involves a disposition of the upstanding flanges which lends strength to the structure without involving undue weight, as, for instance, by arching the foremost guard walls against lateral forces; also in providing a plurality of laterally extending guard flanges, spaced apart by a connecting inclined guard flange; but it is to be understood that while the advantages of the invention are realized in the fullest measure from the employment of all of these details, the invention is not limited to the particular embodiment shown.

In the accompanying drawings—

Figure 1 is a perspective view of a known type of dredging dipper on which a latch guide embodying the present invention, is mounted.

Figure 2 is a front elevation of a latch bar guide embodying the invention,

Figure 3 is a view of the same as seen from the right hand side of Figure 1; and

Figure 4 is a bottom plan view of the latch guide.

5 represents a dredge bucket having a door 6 mounted thereon through the medium of hinges 7, and adapted to be held in closed position by means of a latch bar 8 sliding in guides 9 and 10 mounted on the swinging door and entering its free forward end 11 into the latch plate or keeper 12. As thus far described, the parts may be of any approved known construction.

In implements of the kind described, the keeper 12 is unavoidably located in a position which causes it to encounter serious wear and tear when the implement is in use, for instance, that resulting from dragging over broken rock, catching the rails in cleaning up spillage on dump car tracks, casting the dipper ahead in moving the dredge up to its working, etc.; and as a consequence the keeper must be replaced at intervals at considerable replacement cost. The present invention materially enlarges the life of the keeper 12 by providing upon the hinging door 6 a guard in position to receive the impact of objects lying in the path of the keeper 12, and this guard is, for the sake of economy, incorporated in the same fitting with the latch bar guide 10, so that one and the same attaching base 14 will serve for both the guide and the guard. Moreover, the guard is especially designed with a view to better adapting it to resist the extreme influences which bear upon it in the manipulation of the implement, without involving undue weight or mass of material. To this end, the guard comprises a pair of wings or buffers 13, each constructed with deflecting surfaces inclining in the direction of movement of the implement relatively to the obstructions which it encounters, for instance, inclined surfaces 15 and 16 at the respective sides of the guard which assume positions lateral to the keeper 12 when the door is closed, and the inclined surfaces 17 which incline forwardly toward the keeper; and these surfaces, while preferably provided by the edges of upstanding rear and front laterally extending flanges 15^a and 16^a and forwardly extending flanges 17^a on either side of the keeper, collectively define what is in effect a deflecting plane inclining from the rear outer corner of the guard laterally and forwardly

inward to an apex which approximates the upstanding dimension of the keeper 12, so that the lateral movements of the implement or rearward dragging movements of the 5 same will result in the implement being deflected over obstructions without striking the keeper. Moreover, in its front aspect, as shown in Figure 2, the guard presents a pair of substantial forward buffeting surfaces afforded by the upstanding flanges 16^a, which are strongly braced by the rearwardly extending flanges 17^a, and these buffeting surfaces being presented in advance of the plane of the keeper 12 (the latter being received 10 in the recess 18 of the guard) receive forward impact that might otherwise be exerted against the keeper, and thus protect the keeper in that direction.

As shown in Figure 4, the buffeting surfaces 16^a, afforded by the upstanding flanges of that designation, curve rearwardly, thus adapting them to serve as deflecting surfaces, and besides presenting an arched and consequently stronger structure to receive the 20 forces which the guard encounters in that direction. Continuance of the rear laterally extending flanges 15^a to the guide 10, as shown at 19, lends additional strength in the lateral direction, besides constituting 25 brackets between the guide 10 and its attaching base 14.

I claim:

1. In combination with the body member and the door member of an excavating implement of substantially the character described, a bolt mounted on one of said members a keeper mounted on the other and a keeper guard mounted upon the member which carries the bolt in position to receive 35 impact of objects in the path of the keeper during the movement of the implement when in use.

2. A keeper guard for mounting upon excavating implements having swinging doors and latches; said guard being adapted for attachment to the member of the implement other than the one which carries the keeper and being constructed with a recess that receives the keeper when the door is closed 45 and a pair of buffers in position to stand on either side of the recess and adjacent to the keeper.

3. A keeper guard for excavating implements having latched doors, said guard comprising a pair of wings and adapted to be mounted upon the door of the implement in position to stand adjacent to the keeper when the door is closed; said wings being spaced apart to receive the keeper between them and 55 extending to the fixed plane of the keeper.

4. A keeper guard for excavating implements having doors with latch bolts and keepers, said guard having an attaching base adapted for mounting it upon the implement 60 adjacent to the keeper and being constructed

with a pair of wings spaced apart to admit the keeper between them and having buffing surfaces rearwardly inclined from the plane of the keeper.

5. A keeper guard, comprising an attaching base and a pair of buffers on said base positioned to provide a keeper receiving space between them; each buffer comprising front and rear laterally extending flanges 70 upstanding from the plane of the base.

6. A keeper guard, comprising an attaching base and a pair of buffers on said base positioned to provide a keeper receiving space between them; each buffer comprising front and rear laterally extending flanges 80 upstanding from the plane of the base; said flanges having outer edges inclined away from the plane of the base and toward the position of the outer end of the keeper which they are to protect.

7. A keeper guard, comprising an attaching base and a pair of buffers on said base positioned to provide a keeper receiving space between them; each buffer comprising front and rear laterally extending flanges 85 upstanding from the plane of the base; the forward laterally extending flanges of the buffers being diverted in the direction of the plane of the base and rearwardly from the 90 plane of the keeper when in said receiving space.

8. A keeper guard, comprising an attaching base and a pair of buffers on said base positioned to provide a keeper receiving space between them; each buffer comprising front and rear laterally extending flanges 100 upstanding from the plane of the base; the forward laterally extending flanges being curved in the direction of the plane of the base and rearwardly from the keeper receiving space and developing arched front walls presented against impact in a direction transverse to the plane of the keeper.

9. A combined latch bolt guide and keeper guard, comprising an attaching base, a bolt guide on said base, and a pair of buffers 110 upstanding from the plane of said base on either side of and perpendicularly to the movement of the bolt in said guide; said buffers comprising laterally extending flanges integral with said guide and base.

10. A combined latch bolt guide and keeper guard, comprising an attaching base, a bolt guide defining bolt movement in a plane parallel with said base, and a pair of buffers upstanding from the plane of said base on either side of said guide; said buffers comprising front and rear laterally extending flanges upstanding from said base, some 120 of said flanges being integral with and braced by the guide.

11. A combined latch bar guide and keeper guard, comprising an attaching base, a guide upstanding from the plane of and defining a path of bolt movement parallel 125

with said base, laterally extending rear flanges integral with said guide and base, and laterally extending front flanges all upstanding from the plane of said base, and 5 forwardly extending flanges uniting the front flanges with the rear flanges.

12. In combination with the body member and the door member of an excavating implement of substantially the character described, a bolt mounted on one of said members, a keeper mounted on the other thereof, and a keeper guard mounted upon the member which carries the bolt in position to receive impact of objects in the path of the keeper during the movement of the implement when in use; said keeper having a recess which receives the keeper at the closing of the door and permits the guard to stand on either side of the keeper. 15

20 13. In combination with the body mem-

ber and the door member of an excavating implement of substantially the character described, a bolt mounted on one of said members, a keeper mounted on the other thereof, and a keeper guard mounted upon the member which carries the bolt in position to receive impact of objects in the path of the keeper during the movement of the implement when in use; said guard having an attaching base adapted for mounting it 25 upon the implement adjacent the keeper and being constructed with a pair of wings upstanding from the attaching base, said wings being spaced apart to admit the keeper between them at the closing of the door and 30 having deflecting surfaces inclined toward the free end of the keeper. 35

Signed at Minneapolis, Minn., this 31st day of August, 1925.

ERNEST EDGAR CRANE.
